UNITED STATES PATENT OFFICE.

HELEN A. PRINCE, OF PORTLAND, MAINE.

SURGICAL CORSET.

1,137,899.

Specification of Letters Patent.

Patented May 4, 1915.

Application filed June 5, 1914. Serial No. 843,133.

To all whom it may concern:

Be it known that I, HELEN A. PRINCE, of Portland, in the county of Cumberland and State of Maine, have invented certain new and useful Improvements in Surgical Corsets, of which the following is a specification.

My invention relates to a corset adapted to be worn by women who have been subjected to an abdominal surgical operation. In many abdominal operations women are left with a vertical scar extending centrally over the abdomen. Such scars are extremely sensitive and the ordinary corset with its rigid fastening steels cannot be worn.

The object of my invention is to produce a corset which while having the appearance and characteristics of the ordinary corset is free from any rigid part liable to bear along the center line of the abdomen.

A further object is to provide an abdominal supporter in connection with the corset which supports the abdomen below the lower end of the corset proper with a gentle support at the center line.

These objects I carry out by means of the corset hereinafter described and claimed.

My invention may best be understood by reference to the accompanying drawing, in which is shown a corset constructed in accordance with my invention.

In the drawing, Figure 1 is a perspective view of my corset, Fig. 2 is a view showing the abdominal supporter, and Fig. 3 is a view of a tab used in connection with the corset.

In the drawing, α represents the body of the corset which may be constructed in any well known manner.

According to my invention the fastening steels e are located a short distance at one side of the center line of the front and attached to one of said fastening steels is a strip of cloth b preferably about 3 inches in width and free from any stays or stiffening devices.

The abdominal supporter designated generally by D is made up of a relatively wide band formed of elastic webbing at each end with a section of flexible cloth in the center corresponding to the strip b of the corset

proper. As here shown, each end of the supporter D is formed of horizontally disposed strips of elastic webbing d and d' having eyelets e' at the ends. The central section d^2 is of flexible cloth and is united to one of the end sections by a row of snap fasteners e .

The abdominal supporter is secured to the body of the corset on the inside by lacing cords f which pass through the eyelets e' in the supporter D and through eyelets a' formed in the corset body. That portion of the corset to which the supporter D is laced has a vertical gore which forms a downwardly extending flap a^2 . The lacing holes a' are formed along each side of the gore and the lacing cords f not only secure the supporter D in place but they also bring the edges of the gore together. Thus the lacing cord f permits regulation of the tension of the supporter and also the fit of the corset around the hips and also gives a yielding tension on the hip portion of the corset. The number and location of the eyelets a' are such that the supporter may be adjusted vertically.

For the purpose of securing a sanitary napkin when the same is required I provide a tab g which has snap buttons g' adapted to engage fasteners b' in the lower end of the strip b . This tab can be easily and quickly applied and removed. The tab is made with a section of elastic webbing g^2 which is inserted in the middle with a strip of plain cloth g^3 below to which the napkin may be pinned.

A corset constructed in this manner may be worn with comfort by a woman having a sensitive scar in the center of the abdomen and it also makes an easy and comfortable corset for general use since there is no harsh pressure on the solar plexus, a point which is sensitive in most persons.

In removing the corset the fastening steels are unbuttoned in the usual manner and the abdominal supporter is separated by releasing the snap fasteners e . The corset is put on in a similar manner.

I claim;—

A surgical corset having in the front thereof a pair of fastening steels extending

100

vertically over the abdomen and at one side of the center thereof, a relatively narrow strip of unstayed flexible cloth secured to one of said steels and forming the central portion of the corset front and an abdominal supporter below said strip consisting of a horizontally disposed band composed of two end sections of elastic webbing and a cen-

tral section of cloth forming a continuation of said strip. 10

In testimony whereof I have affixed my signature, in presence of two witnesses.

HELEN A. PRINCE.
